UNITED STATES PATENT OFFICE.

INGENUIN HECHENBLEIKNER, OF CHARLOTTE, NORTH CAROLINA, ASSIGNOR TO
CHEMICAL CONSTRUCTION COMPANY, OF CHARLOTTE, NORTH CAROLINA, A COR-
PORATION OF NORTH CAROLINA.

COOLING APPARATUS.

1,331,500.

Specification of Letters Patent.

Patented Feb. 24, 1920.

Application filed October 17, 1918. Serial No. 258,626.

To all whom it may concern:

Be it known that I, INGENUIN HECHENBLEIKNER, a citizen of the United States, residing at Charlotte, in the county of Mecklenburg and State of North Carolina, have 5 invented certain new and useful Improvements in Cooling Apparatus, of which the following is a specification.

In the manufacture of nitric acid, particularly from gases containing nitrogen oxids resulting from the treatment of air by the electric arc, or nitrogen oxids obtained from other sources, it is necessary or desirable that the gases be cooled to reduce 10 their temperature and also oxidized to convert the nitric oxide (NO) to nitrogen per-oxid (NO₂).

The object of the present invention is to provide an improved apparatus for cooling 20 these or other gases in nitric acid processes; but the invention is not limited to this use, since the apparatus may be utilized wherever it may be found suitable.

The cooling of large bodies of gases incident to the processes referred to is a matter of considerable difficulty, and the present apparatus has been designed to provide a rapid and efficient means for the desired purpose. It embodies in one of its forms an 25 elongated chamber or passage through which the gases flow and depending into this chamber are a multiplicity of what I call cooler tubes through which water is caused to flow so that the gases in passing through 30 the conduit flow around or between the tubes, thereby exposing a large surface for the heat exchange action. Each tube contains within the same a filler or inner section which displaces most of the capacity of 35 the tube and causes the water to flow in a film or relatively thin sheet in contact with the inner surface of the wall of the tube. The tubes are of the spur type, that is, they are closed at the lower end, water being 40 supplied through a central pipe to the bottom of the tube and rising as it is heated to the top where it overflows into troughs.

Figure 1 is a vertical section of one of the tubes. Fig. 2 is a vertical section of part 45 of an apparatus illustrating the manner in which the tubes are used. Fig. 3 is a vertical section taken on a plane at right angles to the plane of Fig. 2.

My U. S. Patent No. 1,311,395, which is a division of this case, shows the structure 55 containing the chambers in which the cooling tubes are used. Each of the cooling chambers is provided with a multiplicity of depending cooler tubes which extend through openings in the roof or top of the 60 chambers as shown in said patent. These tubes may be made of any suitable material. Those in the chambers 1 and 2 of said patent are preferably acid proof iron, because of the high temperatures. Those in the chamber 65 3 of said patent may be stoneware. A tube is shown in detail in Fig. 5 of said patent. It comprises an outer or spur tube 20, closed at the bottom and open at the top. Within this outer tube is a metal drum 70 or filler consisting of a cylinder 21 closed at the top and bottom, and provided at its lower end with a projecting foot 22 which rests upon the bottom of the outer tube and supports the filler therein. The filler is also 75 spaced from the outer tube by spacers 23 thereby forming an annular space of small area through which the water flows upwardly in contact with the inner surface of the outer tube. Water is supplied to the 80 bottom of each tube by a central pipe 24 which extends lengthwise through the drum, and this pipe has a funnel 25 at the top by which it is supplied from any suitable water supply. This supply conveniently 85 consists of a system of piping indicated in Fig. 2 of said patent. Obviously any convenient system of water supply may be used. It is to be noted, however, there is a separate water supply to each tube and a separate 90 overflow from each tube and the water does not pass through one tube after passing through another.

The gases to be cooled are conducted back and forth through the chambers as described 95 in said patent and in passing through the cooling chambers they flow between or in contact with the depending cooler tubes in the cooling chambers, these cooler tubes being supplied with a flow of water in the 100 manner indicated. The cooler tubes are particularly advantageous with respect to the exposure of a large surface for heat exchange and the use of a comparatively small amount of water because of the film 105 arrangement, and also with respect to the

convenience of inserting and removing the same without disconnecting or taking down masonry constructions.

I claim:

- 5 1. A tube for a gas cooler, comprising an outer tube closed at one end and open at the other, and an inner displacing member depending into the tube and provided with a supply pipe for cooling fluid with its outlet 10 near the closed end of the outer tube.
2. A tube for a gas cooler, comprising an outer tube closed at the lower end and open at its upper end, a displacing drum depending into the tube and spaced therefrom to 15 form an annular passage between the tube

and the drum, and means to supply cooling fluid to the lower end of the tube.

3. A tube for a gas cooler, comprising an outer tube closed at its lower end and open at its upper end, an inner drum depending 20 into the tube and spaced therefrom, and a water supply pipe extending through the drum and opening into the tube near the bottom thereof.

In testimony whereof, I affix my signature 25 in presence of two witnesses.

INGENUIN HECHENBLEIKNER.
